CHARLES C. TAYLOR, OF WASHINGTON, DISTRICT OF COLUMBIA, ASSIGNOR, BY MESNE ASSIGNMENTS, TO UNION TYPEWRITER COMPANY, OF JERSEY CITY, NEW JERSEY, A CORPORATION OF NEW JERSEY.

TYPE-WRITING AND COMPUTING MACHINE.

1,032,347.

Specification of Letters Patent.

Patented July 9, 1912.

Application filed July 15, 1911. Serial No. 638,693.

To all whom it may concern:

Be it known that I, CHARLES C. TAYLOR, citizen of the United States, and resident of Washington, District of Columbia, have 5 invented certain new and useful Improvements in Type-Writing and Computing Machines, of which the following is a specification.

My invention relates to computing machines and more especially, though not exclusively, to combined typewriting and computing machines.

In some computing machines provision is made for setting the mechanism for different characters of arithmetical operation, such for example, as addition and subtraction. Where a machine is arranged for addition and subtraction the great majority of the items are usually added, and it 10 usually happens that not more than one or two numbers need be subtracted at a time. In some combined typewriting and computing machines the ordinary use of the machine is to add a column of figures and then 15 set the machine for subtraction to write the total, said total being subtracted from itself, thus bringing the register to zero. In this case it is only the total that is subtracted and after that operation has been effected, 20 it is necessary to set the machine again immediately for addition. In some cases a discount has to be subtracted out first and then the remainder written as a total and 25 subtracted out. In such a case there need 30 to be two consecutive subtractions after which the machine should again be set for addition. In using these machines as heretofore constructed, it has been necessary for 35 the operator to charge his mind with the 40 resetting of the machine for addition and in case of his forgetting to reset it, the first items of the next column of figures will be 45 subtracted instead of added and the work will be spoiled.

The principal object of the present invention is to provide means for automatically 50 restoring the computing mechanism to a setting for addition after a single subtraction in case the character of the work calls for but one subtraction or after a predetermined plurality of subtractions in case the character of the work calls for more than one. By this means the operator is relieved

of the necessity of keeping this change or adjustment in mind and is also free from 55 the loss of time and chance of error that would result from any failure to reset the machine at the right time.

To the above and other ends which will appear hereinafter, my invention consists 60 in certain features of construction and combinations and arrangements of parts, all of which will be fully set forth herein and particularly pointed out in the claims.

One embodiment of my invention is illustrated 65 in the accompanying drawings which are all on an enlarged scale and in which—

Figure 1 is a front elevation of so much of the combined typewriting and computing machine as is necessary to illustrate the application of my invention thereto. Fig. 70 2 is a side elevation of the same. Fig. 3 is a plan view partly in section. Figs. 4, 5 and 6 are fragmentary views of certain parts 75 of the mechanism, shown in different positions in the different views to illustrate the operation of the mechanism when arranged to restore the computing mechanism to addition after two consecutive subtractions. 80 Fig. 7 is a view of nearly the same parts but with the addition of a means for limiting the machine to one subtraction at each setting.

In the drawings I have illustrated an application 85 of my invention to a Wahl adding machine mounted as an attachment to a Remington No. 11 typewriter, this being a combination of computing and typewriting mechanisms in extensive use and well-known 90 in the art.

The main frame of the Remington typewriter comprises a base from which rise corner posts 1 which support a top plate 2. The machine also comprises a carriage arranged 95 to travel back and forth across the top plate 2 and carrying a platen against which types 3, mounted on front-strike type bars 4, are adapted to strike. These types are operated by printing keys 5 mounted on key levers 6 which are suitably connected with the type bars 4 and with an escapement that controls the step-by-step feed of the carriage. The Wahl adding attachment includes an actuator 7 having a frame that includes a casting 8 which stands about ver-

tically in front of the upper part of the typewriter to which said casting is secured by means of brackets 10 fastened to the top plate 2 of said typewriter. Said actuator 5 also includes a series of levers 11 which are connected by links 12 with those key levers 6 that are arranged to write numerals. The levers 11 constitute parts of a differential operating mechanism that turns a master 10 wheel 13 a number of teeth corresponding to the digit written. The Wahl machine also includes a carriage 14 which consists essentially of a long bar of the prismatic cross section shown in Fig. 2 and arranged above 15 the actuator and in front of the casting 8, said carriage being supported in part by said casting through the medium of certain rollers 15 which are journaled on the casting and coöperate with the carriage about 20 in the plane of the master wheel 13. Said carriage has arms 16 projecting from its ends and formed with vertical slots 18 through which pass screws 19 threaded into arms 20 projecting forward from the typewriter carriage. These connections cause the 25 computer carriage 14 to move in unison with the typewriter carriage and they also assist in supporting the computer carriage. On the carriage 14 one or more adding heads or 30 registers 21 may be supported, said adding heads being adjustably secured at any desired positions along the carriage 14 by means of a latch lever 22 that coöperates with notches 23 in the carriage 14. Only 35 one adding head is shown in the present case. Said adding head contains or includes register wheels 24 which are in gear with certain gear wheels 25, which gear wheels are adapted to mesh one at a time with the 40 master wheel 13, so that the travel of the carriage brings one denomination after another of the register under the control of the actuator. The casing of the adding head includes two side plates 26 and 27. A 45 roller 28 is provided at the front of the actuator to guide the adding head across the master wheel with greater precision. The master wheel 13 is turned in one direction or the other for addition or subtraction by 50 means that include a train of sliding change gears one of which is shown at 30. These gears are controlled in their sliding or change motion by means of a rod 31 projecting toward the left from a housing 32 that 55 incloses parts of the actuating mechanism. When the rod 31 is pushed inward or toward the right to the position shown in the drawings the machine is set for addition and when this rod is pulled out to the limit of its 60 motion toward the left the machine is set for subtraction. A handle 33, here shown as consisting of a plate or bar of sheet metal projecting toward the front of the machine, is secured to the end of the rod 31 by means 65 of a screw 34 threaded into the end of the rod as shown in Fig. 3. In one form of the Wahl machine, as heretofore constructed, such a handle has been secured by an ordinary screw but in the present instance I have made the head of the screw elongated into 70 a rod 35 for a purpose which will presently appear. In order to prevent the handle 33 from turning a guide pin 36 is provided, said pin projecting from the housing 32 through a suitable hole in the handle 33. The pin 35 projects through an ear 37 of a bracket 38 which is secured to the casting 8 by screws 40. A spring 41 is coiled about the rod 35 and is compressed between the ear 37 and the enlarged part of said rod that 75 serves as a sort of head for the screw 34. The tension of this spring tends to hold the rod 31 in position for addition and when said rod is pulled toward the left by the handle 33 to set the machine for subtraction, this spring is capable of restoring said rod to its normal position. In order to hold the rod temporarily in position for subtraction, a pawl or latch 42 is pivoted between ears 43 of the bracket 38 on a pivot 80 screw 44. Said pawl, being overweighted on its right-hand side, is adapted to fall by gravity into engagement with a short arm 45 which constitutes a rearward extension of the handle 33. 85

I have shown in the drawings means adapted to move the pawl 42 automatically out of engagement with the arm 45 after two successive subtractions. Said means includes a bar 46 slidably mounted above the 90 actuator on two pins or screws 47 and 48. The bar 46 lies just in front of the lower part of the carriage 14 and above the body of the actuator and below the extreme rear part of the adding head. The screw 47 is 95 threaded into a bracket 50 which is secured by screws 51 to the upper edge of the casting 8. Said screw 47 passes through a slot 52, Fig. 4, in the bar 46, said slot being wider than the diameter of the screw. The screw 48 passes through a slot 53 in the bar 46, said slot being of such a length as to 100 define the possible sliding motion of the bar. The screw 48 is threaded into a bracket 54 which is secured to the casting 8 by screws 105 55 which preferably pass through short slots in said bracket for the purpose of permitting a certain amount of adjustment to the screw 48, which screw serves as a stop to limit the motion of the bar 46. The brackets 38, 50 and 54 all pass beneath the carriage 14 and are bent up at their forward ends to support the several parts. The bar 46 has a depending arm 56 to which is connected a restoring spring 57, one end of 110 which is secured to a bracket 58 suitably fastened to the casting 8. The spring 57 tends to pull the bar 46 lengthwise toward the right and it also tends to rock the bar about the pin 48 as a center, this last by 115 120 125 130

reason of the fact that the spring is connected with the bar below the said pin 48. The bar 46 has a lug 60 projecting upward therefrom, said lug preferably consisting of an arm pivoted to the side of the bar on a screw 61. This pivoted part has projecting therefrom a second arm 62 that lies between the two branches of a spring 63 which is coiled or bent about a screw 64 threaded 10 into the bar 46. The two ends of the spring tend to approach each other and their motion is limited by a pin 65 projecting from the bar 46. The construction is such that the spring 63 normally holds the lug 60 in its upright position shown in the drawings but said lug can yield in either direction upon application of force sufficient to bend the spring. The lug 60 stands in the path of motion of a part 66 of the right-hand 20 cover plate 27 of the adding head, this part 66 being made to project a little below the corresponding part of the left-hand casing plate 26 so that said left-hand plate will not engage the lug 60 but said lug will be engaged by the right-hand casing plate. 25

The pawl or latch 42 has two teeth 67 and 68 formed thereon, the tooth 67 being longer than the tooth 68 as clearly shown in the drawings. When the adding machine 30 is set for subtraction, as indicated by the position of the arm 45 in Fig. 4, the ear 66 engages the lug 60 at about the time the master wheel is moving into engagement with the register wheel of last order and 35 when said register wheel is in engagement with the master wheel the bar 46 has been pushed over from its normal position shown in Fig. 1 to the position shown in Fig. 4, where the left-hand end of said bar is in 40 engagement with the tooth 67. After the digit of last order has been written the carriage makes another step to the left, which moves the bar 46 to the position shown in Fig. 5, thus raising the latch 42 about half 45 way out of engagement with the arm 45. The pawl will be held in this position by friction due to the tension of the spring 41. When the carriage is withdrawn toward the right, the bar 46 resumes its normal position 50 shown in Fig. 1, being pulled back to that position by the spring 57. In moving back to normal position the end of the bar 46 is slightly elevated by the tooth 68, this motion being permitted by the extra width 55 of the slot 52; and when the bar is snapped down from off the tooth it is drawn to its lower position again by reason of the off-set position of the spring 57.

The operation just above described takes 60 place in subtracting out the discount at the end of the adding operation. The next operation of the machine is to subtract out the total or balance and at the end of that operation the machine should be restored to 65 condition for addition. When in the opera-

tion of subtracting out the total, the adding machine carriage reaches the point where the master wheel is in engagement with the register wheel of lowest order, the bar 46 will have been moved to the position shown 70 in Fig. 4 but this time it will engage the tooth 68 instead of the tooth 67. When the carriage takes its next step after the writing of the last digit the parts will move to the position shown in Fig. 6, thus releasing 75 the arm 45 and allowing the spring 41 to restore the mechanism to its setting for addition. In case the carriage is moved entirely past the adding column in either direction the lug 60 can yield about its pivot 80 61 against the tension of the spring 63 and permit the carriage to pass, the lug snapping back to normal position after the carriage has passed.

It will be noted that the mechanism above 85 described is not only adapted to restore the adding mechanism to addition in case of two consecutive subtractions from the same adding head, but it would also restore the mechanism to addition after two successive 90 subtractions one from each of two adding heads, in case there should be that many on the machine and in case there was no discount to be subtracted out. It will also be understood of course that the number of 95 subtractions permitted by the automatic mechanism can be varied by suitable variation in the mechanism itself. One such variation is provided for in the device as shown, that is to say, provision is made for 100 causing the latch 42 to be tripped off after only one subtraction. To this end the pawl 42 is formed with a slot 70, Fig. 4, and one of the ears 43 is formed with a threaded 105 hole 71, Fig. 1. These parts are so related that if a screw 72, Fig. 7, having a reduced end, be screwed into the hole 71 so that said reduced end enters the slot 70, then said screw will limit the downward motion of the pawl 42 to the position shown in Fig. 7 110 in which the pawl is only partially engaged with the arm 45 and in which the tooth 68 lies in the path of the bar 46. When the screw 72 is in position as shown in Fig. 7, the tooth 67 is inoperative and the latch will 115 be released after a single subtraction.

It will, of course, be understood that various changes can be made in the details of construction and arrangement without departing from my invention. 120

What I claim as new and desire to secure by Letters Patent, is:—

1. In a combined typewriting and computing machine, the combination of typewriting mechanism, computing mechanism 125 for registering numbers written by said typewriting mechanism, means adjustable by hand at the will of the operator to set said computing mechanism from addition to subtraction, and means for resetting said 130

adjustable means, said resetting means constructed to act automatically at the end of a subtracting operation.

2. In a combined typewriting and computing machine, the combination of typewriting mechanism, computing mechanism for registering numbers written by said typewriting mechanism, means adjustable by hand at the will of the operator to change the character of the arithmetical operation performed by said computing mechanism, and means for restoring said adjustable means, said restoring means arranged to act automatically at the end of the writing and registering of a number.

3. In a computing machine, the combination of a register, an actuator, a traveling carriage for bringing one denomination after another of said register under the control of the actuator, means settable by hand at the will of the operator to change the character of the arithmetical operation performed, and means controlled by said carriage for automatically resetting said settable means.

4. In a computing machine, the combination of a register, an actuator, a traveling carriage for bringing one denomination after another of said register under the control of said actuator, said register being adjustable with relation to the travel of said carriage, and means controlled by said register for setting the mechanism to change the character of the arithmetical operation performed.

5. The combination of typewriting and computing mechanisms for writing and registering numbers, said computing mechanism being capable of the operations of addition and subtraction and comprising a register, an actuator, a traveling carriage for bringing one denomination after another of said register under the control of said actuator, said register being adjustable with relation to the travel of said carriage, and means comprising a part adjustable with said register for changing the operation performed in said register.

6. In a combined typewriting and computing machine, the combination with typewriting mechanism including a traveling carriage, computing mechanism including a carriage that travels in unison with the typewriter carriage, an adding head mounted on said computer carriage and adjustable lengthwise thereof, an actuator for said adding head, means settable for addition and subtraction, and means for setting said settable means, said setting means comprising a part on said actuator and a part on said adding head, said parts being timed to act at the end of a registering operation.

7. In a combined typewriting and computing machine, the combination of typewriting mechanism including a carriage,

computing mechanism for registering numbers written by said typewriting mechanism and including means settable to add or subtract the numbers written, a spring for normally holding said settable means set for addition, a latch for holding said settable means for subtraction, and means controlled by said carriage for tripping said latch. 70

8. In a combined typewriting and computing machine, the combination of typewriting and registering mechanism for writing and registering numbers, means adjustable to change the registering operation from addition to subtraction, and means for automatically restoring said adjustable means, said restoring means being arranged to restore said adjustable means after a predetermined plurality of numbers have been subtracted. 75 80

9. In a combined typewriting and computing machine, the combination of typewriting and registering mechanisms for writing and registering numbers, means adjustable to set the machine from addition to subtraction, and means for automatically restoring said adjustable means, said restoring means being arranged to restore said adjustable means after a predetermined number of subtractions, and means for changing the number of subtractions required to bring 90 95 said restoring means into action.

10. In a computing machine, the combination of a series of register wheels, means for actuating said wheels one at a time, means for imparting a relative step by step 100 motion between said actuating means and said register wheels to bring one after another of the said register wheels under control of said actuating means, a device adjustable by hand at the will of the operator 105 to change said computing mechanism from addition to subtraction, and means for restoring said device, said restoring means being operated by said step by step moving part. 110

11. In a computing machine, the combination of mechanism for adding and subtracting numbers, means settable for addition and subtraction, and means for automatically changing the setting of said settable 115 means after the registration of a predetermined plurality of numbers.

12. In a computing machine, the combination of mechanism for registering numbers, means settable for addition and subtraction, means for automatically operating said settable means after the registration of a predetermined number of numbers, and means for changing the number of registrations required for operating said settable means. 120 125

13. In a computing machine, the combination of a register, an actuator, a traveling carriage for bringing one denomination after another of said register under the control of said actuator, means adjustable to set 130

the mechanism for addition and subtraction, and means operated by a predetermined plurality of excursions of said carriage for changing said adjustable means.

- 5 14. In a combined typewriting and computing machine, the combination of an actuator, a register, a traveling carriage, a device adjustable to set the mechanism for addition and subtraction, a spring for normally holding said device at addition, a latch for holding said device at subtraction, and means operated by the travel of said carriage for tripping said latch.

- 10 15. In a combined typewriting and computing machine, the combination of an actuator, a register, a traveling carriage, a device adjustable to set the mechanism for addition and subtraction, a spring for normally holding said device at addition, a latch for holding said device at subtraction, and means operated by the travel of said carriage for tripping said latch after a predetermined plurality of excursions of said carriage.

- 15 16. In a combined typewriting and computing machine, the combination of an actuator, a register, a traveling carriage, a device adjustable to set the mechanism for addition and subtraction, a spring for normally holding said device at addition, a latch for holding said device at subtraction, means operated by the travel of said carriage for tripping said latch after a predetermined number of excursions of said carriage, and means for changing the number of excursions required.

- 20 17. In a combined typewriting and computing machine, the combination of a register, a traveling carriage on which said register is adjustably mounted, an actuator, a device adjustable to set the mechanism for addition and subtraction, a spring for normally holding said device at addition, a latch for holding said device at subtraction, means operated by a travel of said carriage for partially tripping said latch, and means operated by a subsequent excursion of said carriage for fully tripping said latch.

- 25 18. In a computing machine, the combination of a register, a carriage on which said register is adjustably mounted, an actuator, means settable to change the mechanism for addition and subtraction, means comprising an abutment on said actuator and an abutment on said register for changing said settable means, one of said abutments being yielding to allow the register to pass the position at which said abutments coöperate.

- 30 19. In a combined typewriting and computing machine, the combination with typewriting and computing mechanisms for printing and registering numbers, said computing mechanism comprising a register, an actuator, and a traveling carriage, of means

settable to change the character of the arithmetical operation performed by the computing mechanism, and means for automatically setting said settable means, said automatic means comprising an abutment associated with the actuator and an abutment associated with the register, one of said abutments being yielding to allow said carriage to move past the point at which said abutments coöperate.

70 20. In a combined typewriting and computing machine, the combination with typewriting and computing mechanisms for writing and registering numbers, said computing mechanism comprising an actuator, a register and a traveling carriage, of means settable to change the character of the arithmetical operation performed by the computing mechanism, a spring for normally holding said settable means in one position, a latch for holding said settable means in another position, a sliding bar for operating said latch, and means whereby the travel of the carriage operates said bar.

75 21. In a combined typewriting and computing machine, the combination with typewriting and computing mechanisms for writing and registering numbers, said computing mechanism comprising a register, an actuator and a traveling carriage, a part settable to different positions to change the character of the arithmetical operation performed by the computing mechanism, a spring for holding said part in one position, a latch for holding said part in another position, a sliding bar for operating said latch, a plurality of teeth on which said sliding bar operates, an abutment on said bar, and a coöperating abutment on said register.

80 22. In a combined typewriting and computing machine, the combination with typewriting and computing mechanisms for writing and registering numbers, said computing mechanism comprising a register, an actuator and a traveling carriage, a part settable to different positions to change the character of the arithmetical operation performed by the computing mechanism, a spring for holding said part in one position, a latch for holding said part in another position, a sliding bar for operating said latch, a plurality of teeth on which said sliding bar operates, an abutment on said bar, and a coöperating abutment on said register, one of said abutments being capable of yielding to allow said traveling carriage to pass beyond the point at which said abutments coöperate.

85 23. In a combined typewriting and computing machine, the combination with typewriting and computing mechanisms for writing and registering numbers, said computing mechanism comprising a register, an actuator and a traveling carriage, a part settable to different positions to change the

character of the arithmetical operation performed by the computing mechanism, a spring for holding said part in one position, a latch for holding said part in another position, a sliding bar for operating said latch, a plurality of teeth on which said sliding bar operates, an abutment on said bar, a co-operating abutment on said register, and

means capable of being set to hold said latch in a partially operated position. 10

Signed at Washington, District of Columbia, this tenth day of July A. D. 1911.
